UNITED STATES PATENT OFFICE.

LOTTIE E. FREEMAN, OF BOSTON, MASSACHUSETTS.

DESIGN FOR A CHILD'S GARMENT.

58,308.

Specification for Design.

Patented July 12, 1921.

Application filed August 23, 1920. Serial No. 405,521. Term of patent 3½ years.

To all whom it may concern:

Be it known that I, LOTTIE E. FREEMAN, a citizen of the United States, residing at Boston, in the county of Suffolk and State of Massachusetts, have invented a new, original, and ornamental Design for a Child's Garment, of which the following is a specification, reference being had to the accompanying drawing, forming part thereof.

In the drawings, the figure is a front elevation of a child's garment showing my new design.

I claim:

The ornamental design for a child's garment, as shown.

LOTTIE E. FREEMAN.
